UNITED STATES PATENT OFFICE.

FELIX MAGUIRE AND OSCAR L. BILLINGS, OF PHILADELPHIA, PA.

CROSS-WALK FOR STREETS.

SPECIFICATION forming part of Letters Patent No. 341,490, dated May 11, 1886.

Application filed June 22, 1883. Serial No. 169,366. (No model.)

To all whom it may concern:

Be it known that we, FELIX MAGUIRE and OSCAR L. BILLINGS, both of the city of Philadelphia and State of Pennsylvania, have invented a new and useful Improvement in Cross-Walks for Streets, of which the following is a specification.

The object of our invention is to provide a cross-walk in which the stones thereof are so protected as to prevent the wearing away and destruction of their adjacent ends and the consequent damage to vehicles and expense of repair resulting therefrom.

In the drawings, Figure 1 is a view in perspective of a cross-walk embodying our invention. Fig. 2 is a detail view in perspective of the plate F of Fig. 1, in an inverted position; and Fig. 3 a longitudinal sectional elevation of the cross-walk shown in Fig. 1.

20 A is the sidewalk, B the street-pavement, and C the curbstone, all of the ordinary and usual construction. D and E are adjacent stones of the cross-walk.

Our invention consists in providing the seam 25 or line of juncture of the stones with a metallic strip or plate, F, so disposed as to cover the seam between the stones and protect the adjacent edges thereof from the ordinary wear of travel.

30 In the drawings, as shown, the plate F is on its under side provided with a longitudinal rib G. This rib is on its sides provided with projections H H and J J. The upper surface of this plate is roughened in any suitable manner to prevent the slipping of animals when stepping thereon. The plate F, when in place, is recessed or let into the body of the stones, so that its upper surface is flush with their upper surfaces. The longitudinal rib G and 40 its projections H H and J J are let into appropriate recesses in the stones, with the result

that the line of juncture thereof is covered and protected and the lateral and vertical displacement of the plate prevented.

It is obvious that the plate F may be placed 45 upon the upper surface of the stones without being let into the body thereof, and that the form and arrangement of the flange G and the projections thereon may be varied without departing from our invention.

50 It will be understood that the improvement described not only prevents the wearing of the adjacent edges of the stones of the cross-walk, and consequent injury to vehicles and animals, but it also obviates the expense of repair of 55 the crossing and the obstruction to travel incident thereto.

Having thus described our invention, we claim—

1. In combination with the adjacent ends of 60 the stones of a cross-walk, a metallic strip or plate provided on its under surface with a longitudinal rib, said plate being disposed upon and over and said rib within the seam of juncture, as specified.

65 2. In combination with the adjacent ends of the stones of a cross-walk, a metallic strip or plate provided on its under surface with a longitudinal rib, said rib being provided upon its side surfaces with projections, said plate 70 being disposed upon and over said rib and its projections within the seam of juncture, as specified.

In testimony whereof we have hereunto signed our names this 8th day of June, A. D. 75 1885.

FELIX MAGUIRE.
OSCAR L. BILLINGS.

In presence of—

WM. C. STRAWBRIDGE,
ISAIAH MATLOCK,
J. BONSALL TAYLOR.

Corrections in Letters Patent No. 341,490.

It is hereby certified that in Letters Patent No. 341,490, granted May 11, 1886, upon the application of Felix Maguire and Oscar L. Billings, of Philadelphia, Pennsylvania, for an improvement in "Cross-Walks for Streets," errors appear in the printed specification requiring correction, as follows: In line 64, page 1, a comma should be inserted after the word "over;" In line 71, same page, a comma and the word *and* should be inserted after the word "over;" and that the Letters Patent should be read with these corrections therein that the same may conform to the record of the case in the Patent Office.

Signed, countersigned, and sealed this 18th day of May, A. D. 1886.

[SEAL.]

Countersigned:

M. V. MONTGOMERY,
Commissioner of Patents.

H. L. MULDROW,
Acting Secretary of the Interior.
